DESIGN FOR AN ENSIGN OR SIMILAR ARTICLE

Alfred Wolff, New York, N. Y.

Application December 16, 1941, Serial No. 104,656

Term of patent 3½ years

To all whom it may concern:

Be it known that I, Alfred Wolff, a citizen of the United States and resident of New York, in the county and State of New York, have invented a new, original, and ornamental Design for an Ensign or Similiar Article, of which the following is a specification, reference being had to the accompanying drawing, forming part thereof.

In the drawing:

Fig. 1 is a plan view of an ensign showing my new design.

Fig. 2 is an end view thereof.

The design is characterized by a border sur-

rounding a centrally disposed field of a color or shade contrasting with that of the border and with the letter V arranged upon the centrally disposed field with the extremities of the legs of the V and the apex thereof projecting over onto the border surrounding the said field and a plurality of stars displayed upon the said centrally disposed field as shown.

I claim:

The ornamental design for an ensign or similar article, substantially as shown and described.

ALFRED WOLFF.
